[57] CLAIM

The ornamental design for a medical liquid container
for enteral feeding of patients, substantially as shown
and described.

DESCRIPTION

FIG. 1 is a perspective view of a medical liquid container
for enteral feeding of patients showing our new
design;

FIG. 2 is a top plan view thereof;

FIG. 3 is a left side elevational view thereof;

FIG. 4 is an end elevational view thereof;

FIG. 5 is an end elevational view thereof, opposite that
shown in FIG. 4;

FIG. 6 is a right side elevational view thereof;

FIG. 7 is a bottom plan view thereof; and

FIG. 8 is a fragmentary perspective view thereof, with
hanger in raised position.
